Helen Berry, New York, N. Y.

Application April 21, 1938, Serial No. 76,658

Term of patent 3½ years

To all whom it may concern:

Be it known that I, Helen Berry, a citizen of the United States of America, residing in city of New York, county of New York, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

The characteristic feature of my design resides in the combination on the dress disclosed of the specific panels of shell tucks on the front and rear of the skirt, in association with the particular blouse section which is yoked and Shirred as shown.

I claim:

The ornamental design for a dress substantially as shown and described.

HELEN BERRY.
